[57] CLAIM

The ornamental design for a “golf bag stand,” as shown and described.

DESCRIPTION

FIG. 1 is a front elevational view of a golf bag stand in accordance with the present invention;

FIG. 2 is a right side elevational view of the golf bag stand of FIG. 1, the left side elevational view being a mirror image thereof;

FIG. 3 is a rear elevational view of the golf bag stand of FIG. 1;

FIG. 4 is a top plan view of the golf bag stand of FIG. 1; and,

FIG. 5 is a bottom plan view of the golf bag stand of FIG. 1.
